UNITED STATES PATENT OFFICE.

WILLIAM J. HOSKYNS, OF DETROIT, MICHIGAN, ASSIGNOR TO THE AUTO ACCESSORIES MANUFACTURING COMPANY, OF DETROIT, MICHIGAN.

CARRIAGE-TOP.

No. 876,905.

Specification of Letters Patent.

Patented Jan. 14, 1908.

Application filed August 10, 1907. Serial No. 387,966.

To all whom it may concern:

Be it known that I, WILLIAM J. HOSKYNS, a citizen of the United States, residing at Detroit, county of Wayne, State of Michigan, 5 have invented a certain new and useful Improvement in Carriage-Tops, and declare the following to be a full, clear, and exact description of the same, such as will enable others skilled in the art to which it pertains 10 to make and use the same, reference being had to the accompanying drawings, which form a part of this specification.

This invention relates to carriage tops; it has for its object an improved frame for carriage tops in which one of the bows is adapted 15 to be unshipped from its place of use when used with an extended top and reshipped to a different position to enable the several bows to be folded into more compact and better 20 arrangement.

In the drawings:—Figure 1, shows the frame in its extended position and the top is indicated as stretched over the frame. Fig. 2, shows the frame in its folded position. 25 Fig. 3, shows the same character of bow used with both a rear and front connection.

The frame is more especially intended to be used with automobile bodies in which it is desired to have a long fore and aft extent 30 of the top.

In Fig. 1, is shown a common form of run-about body with a single removable bow arranged to be extended forward to cover the front part of the boot and the steering 35 gear. In Fig. 3, the same character of bow is shown arranged with respect to a front seat and to a rear seat of a two seated automobile body. Fig. 4, shows the arrangement when the bows used with the front 40 seat of a double seated vehicle are unshipped from the front and assembled in connection with the rear standard.

A vertical bow 1 is secured in the ordinary way to the seat 2, of the automobile body 45 and to this is hinged the bow 3, which is in the usual form and hinged to an eye bar 4, at the base of the bow in the usual way. To the same eye-bar 4, to which bow 3 is 50 connected, may be attached the engaging end 5 of the bow 6 which is of a size to fold into close engagement with the bow 1.

Near the end of the bow 6, is a bent cross-bar or bow 7; this has a curvature in a plane at right-angles to the plane of the bow 6, and 55 is adapted to fold into the curve of the bow

1; when the parts are folded together as shown in Fig. 2. It is also adapted to rise above the plane of the bow 6, when the bow 6 lies in a horizontal position as shown in Fig. 1. Near the spring of the arch of the bow 1, 60 and upon each standard is secured a bearing coupling 8 provided with a pin hole by means of which it may be brought into engagement with the eye at the end of the bow 6, and the parts are adapted to be secured together by bolts or screws that pass through the holes in the bearing coupling 8, and in the terminal 5. When so secured, the bow 6 extends forward in a horizontal position with the bow or arch 7 lying above it and 65 with the front end supported by the cover 9. The bow 6 projecting as it does from near the upper end of the bow 1, may thus be made considerably shorter than it would otherwise require to be made in order that 70 it might carry the carriage top to as great a distance forward as the short bow shown in the drawing will carry the top forward and at the same time by unshipping the bow 75 from the couplings 5 and 8, and bringing the terminal 5 into engagement with the eye-bar 4, the carriage top folds into a convenient short space.

In the form shown in Fig. 3, only a single standard 10 is used at the front, and a single 80 standard 21 at the rear. To the standard 10 is engaged a bow 16, similar in all respects to the bow 6, and one with which the coupling between the terminal 15 and the bearing 18 may be disconnected, and the terminal 15 90 brought into engagement with the attachment 14 in the way previously described. At the rear of the carriage a similar bow 26 is connected by a terminal 25 with the bearing 28 on the standard 21, from which it 95 may be unshipped and reshipped to connect it with attachment 24 when it is desired to fold the same. The standard 10 may be unshipped from the front seat and pivotally connected to one branch of the attachment 100 24, thus assembling all the bows which support the canopy over the rear seat of a two seated vehicle, leaving the front seat entirely without canopy, but assembling the supports where they are practically out of 105 the way and are still easy to get at if occasion requires their use.

What I claim is:—

1. In a carriage top, in combination with a standard bow adapted to be attached to the 110

seat of a carriage, a folding bow provided with a bent cross-bar adapted to engage within the arch of the standard and support the flap of the cover when the folding bow and the standard bow are closed together, an attachment to which said folding bow may be connected at the bottom of said standard bow, and an attachment to which said bow may be connected near the spring of the arch of said standard bow, substantially as described.

2. In a carriage top, in combination with a pair of standard bows, a horizontally disposed bow pivotally attached to each stand-

ard bow near the spring of its arch, means for 15 detaching each horizontal bow from its connection with the standard bow and reconnecting each bow with its standard near the bottom, and means for engaging the two standard bows together, substantially as de- 20 scribed.

In testimony whereof, I, sign this specification in the presence of two witnesses.

WILLIAM J. HOSKYNNS.
